UNITED STATES PATENT OFFICE.

WILLIAM HANLEY, OF EAST ORANGE, NEW JERSEY, ASSIGNEE TO FERGUSON BROS. MFG. CO., OF HOBOKEN, NEW JERSEY, A CORPORATION OF NEW JERSEY.

TABLE.

No. 909,787.

Specification of Letters Patent.

Patented Jan. 12, 1909.

Original application filed June 2, 1908, Serial No. 436,279. Divided and this application filed October 3, 1908.
Serial No. 456,102.

To all whom it may concern:

Be it known that I, WILLIAM HANLEY, a citizen of the United States, and resident of East Orange, in the county of Essex and 5 State of New Jersey, have invented a new and useful Improvement in Tables, of which the following is a specification.

The object of my invention is to provide certain improvements in the construction, 10 form and arrangement of the several parts whereby a strong and durable table may be made at a reasonable cost and in which any unevenness in the top of the table owing to the warping of the wood is entirely obvi- 15 ated.

A practical embodiment of my invention is represented in the accompanying drawings, in which—

Figure 1 is a perspective view of my im- 20 proved table in its unfolded position as in use, the view being taken from a point below the table, Fig. 2 is a top plan view of the table, a portion of the cover and its lining being broken away to more clearly show 25 the means for attaching the top panels to the top side frame and the diagonal supports, Fig. 3 is an inverted plan view of the table with the legs folded, a portion of the side frame being broken away to more clearly 30 show the elongated slot and socket for the reception of the laterally turned upper end of the leg brace, Fig. 4 is a detail section taken in the plane of the line A—A of Fig. 2, looking in the direction of the arrows, Fig. 35 5 is an enlarged detail inverted plan view of the table with the legs in their folded position, Fig. 6 is a horizontal section through a small portion of the top side frame, showing the laterally turned upper end of the 40 leg brace in full lines engaging the socket at the outer end of the elongated slot and in dotted lines in the position it assumes as it is started along the slot during the folding of the leg, Fig. 7 is a very much enlarged section showing the means for securing the 45 table cover to its top, and Fig. 8 is a detail perspective view of one of the angle irons which connect the diagonal supports to the top side of the frame of the table.

50 The four top side rails which form the top side frame are denoted by 1, 2, 3 and 4, which rails are firmly united at the corners of the table. The inner edges of the tops of these side rails are cut away to form

angular recesses 5 for the reception of the 55 outer ends of the panels 6 which form the top of the table.

Diagonal supports 7 and 8 have their ends secured to and spaced from the side rails of the top by angle irons, each composed of 60 a branch 9 adapted to be rigidly secured to the side rail, a diagonal branch 10 adapted to be rigidly secured to the end of the diagonal support, and an intermediate portion 11 extending at right angles to its branch 9. 65

In the present instance, screws 12 are shown for securing the branches 9 of these angle irons to the side rails and screws 13 are shown for securing the diagonal branches 10 of these angle irons firmly embedded with- 70 in the ends of the diagonal supports.

To prevent the top of the table from becoming warped or uneven, panels 6 are made in varying lengths extending only partway across the top of the table. These panels 75 have their outer ends resting in the angular recesses 5 and their inner ends resting upon diagonal supports 7, 8. These panels may be rigidly secured to the side rails and the diagonal supports by any suitable means, 80 as, for instance, by small nails or brads 14.

The top of the table is further reinforced by strips 15 extending along the under faces of the panels 6 between the diagonal supports 7, 8, intermediate the ends of said 85 diagonal supports and their point of intersection.

The cover 16 of the table may be of any desired material such, for instance, as felt and a lining 17 may be interposed between 90 the cover 16 and the upper faces of the panels 6. This cover 16 is secured around its edges within the angular recesses 5 between the outer ends of the panels 6 and the walls of the said recesses. In the present 95 instance, the cover is secured in position by inserting liquid glue into the space above described and then forcing the edges of the cover firmly into said glue.

The four legs of the table are denoted by 100 18, which legs are arranged to individually fold around the sides of the table adjacent to their respective top side rails in the plane of the top side frame. Each leg is hinged by a screw 19 between the intermediate portion 11 of the angle iron and a spacing block 105 20 at the corner of the table.

The free end of each leg when folded is

held frictionally in its folded position by forcing the legs outwardly toward its side rail, a sufficient distance to permit the free end of the leg to pass by the outer end of 5 one of the diagonal supports 7, 8.

The tendency of the leg to spring back to its normal position will cause the end of the diagonal support to hold the leg in its folded position.

10 Each leg is provided with a brace 21, the lower laterally turned end 22 of which is pivoted to the leg at a distance from its hinged end and the laterally turned upper end 23 of which is fitted to enter a socket 24 15 in the top side rail when the leg is in its unfolded position.

As the leg is folded, the laterally turned upper end of the brace 21 is fitted to travel along within an elongated slot 25 in the top 20 side rail, the inner end of which slot terminates at the socket 24.

A keeper 26 is secured to the top side rail in position over the mouth of the socket 24 and the inner end of the elongated slot 25, 25 which keeper is spaced a sufficient distance from the mouth of the socket to permit the laterally turned upper end of the brace to be withdrawn from the socket but not from the elongated slot. This keeper is sufficiently long to permit the laterally turned 30 upper end of the leg brace to travel a very short distance along within the elongated slot 25 as the leg is folded before said laterally turned upper end of the brace is released 35 from the protective influence of the said keeper.

By providing the table with the diagonal supports and forming the top panels of the gradually increasing lengths from the 40 corners to the center of the table, I am enabled

to produce a table top which will be very strong and which will resist all tendency to twist or warp out of shape. Furthermore, the angle irons which secure the diagonal supports to the top side frame not only 45 serve to strengthen the table at the corners but also serve as a part of the hinged connection for the folding legs of the table.

The parts shown and described but not claimed herein, form the subject matter of 50 my co-pending application Serial No. 436279, filed by me June 2, 1908, of which the present application is a division.

What I claim is:

1. In a table, a top side frame, supports 55 extending diagonally entirely across the table and secured to said top side frame and a top composed of panels of varying lengths having their outer ends secured to the said top side frame and their inner ends resting 60 on and secured to said diagonal supports.

2. In a table, a top side frame, diagonal supports secured thereto, said supports intersecting at their middle portions, a top composed of panels having their outer ends secured to the top side frame and their inner ends secured to said diagonal supports and additional strips extending along the under 65 faces of the panels between the diagonal supports intermediate the ends of said supports and their point of intersection.

In testimony, that I claim the foregoing as my invention, I have signed my name in presence of two witnesses, this 28th day of September 1908.

WILLIAM HANLEY.
